METHOD FOR SECONDARY RECOVERY
OF OIL

Roy Cross, Kansas City, Mo.

Application September 6, 1943, Serial No. 501,409

1 Claim. (Cl. 166—21)

This invention relates to a method of increasing the amount of oil recovered from oil wells. It applies more particularly to wells which produce oil that has a high viscosity or high cold test.

One of the objects of the invention is to provide a new and improved cyclic system of adding a fluxing agent to oil wells to reduce the viscosity of the oil therein, the fluxing agent being a light petroleum oil of the same general character as the oil in the formation of the well and acting as a solvent for said oil.

Another object is to provide a new and improved method of heating the oil in the formation to reduce the viscosity and increase the rates of flow in the interstices of the mineral particles of the formation in such manner that as little heat as possible is dissipated into the non-oil bearing formations adjacent to the oil bearing formations.

Another primary object of the invention is to increase the rate of flow from the region of the well where the treating takes place to the region of the well from which the oil is lifted.

As an illustration of the application of this invention, I refer to oil produced in Allen County, Kansas. There is a vast quantity of this oil, in many cases amounting to 30,000 or more barrels per acre. By the ordinary method of extraction with wells approximately 400 feet apart, the total amount of oil taken out in a period of 20 years has been about 1%, or 300 barrels per acre. By the method of this invention the amount taken out, depending upon circumstances, will vary from 10% to 50%, or from 3000 to 15,000 barrels per acre. This particular oil has a specific gravity of 0.939 or A. P. I. gravity of 19.2°, a viscosity of 956 Saybolt Universal, cold test of —10° F., a color of over 15,000, a flash point of 265° F., residue and water of 1% and contains no natural gasoline or naphtha. By cracking, it will yield well over 60% of gasoline, however, so the oil is basically of considerable value and it contains a small amount of sulphur. The oil is excellent stock for lubricating oil and it is practically free from wax. In other words, it has practically the same value as light crude.

In this invention, the method may be illustrated by one particular lease where there is a daily production of 100 to 200 barrels of the heavy oil, each well producing about two barrels per day. In this case, this crude oil is subjected to an incipient cracking temperature of approximately 800° F. in a continuous tube still. The moment the oil attains this temperature it is

allowed to vaporize by its own self-contained heat so that from 15% to 50% passes into the vapor state depending upon the specific method of operation. The vapors from this flash distillation are introduced into the well at the level of the formation bearing the oil. The rock pressure in this particular lease is 250 pounds per square inch. Sufficient pressure is carried against this formation so that the desired amount of vapors will enter the formation. Ordinarily this is over 250 pounds per square inch, although it varies in different wells. The temperature of the entering vapor will vary ordinarily from 250° F. up to 750° F. When it is desirable that the residue or fuel oil have a low viscosity, then the temperature of the vapors is decreased but if an asphaltic residue is desired, then the temperature of the vapors is increased. These vapors enter the oil formation most easily at the point where there is oil which has an affinity for the oil vapors, thus the heat is selectively introduced into the oil in the formation, rather than being wasted in the heating up of the adjacent sand or rock and water. The input well or well into which the vapor is introduced is centrally located in respect to other wells. Normally there will be eight wells immediately surrounding the input well, in some cases 24 or more wells. There should preferably be not less than 4 wells or preferably not more than 24 wells surrounding each input well, although if the formations are very porous the oil may be forced to migrate by reason of its lower viscosity to considerable distances. With this lowered viscosity, the oil will preferentially flow into the adjacent well from which the oil is pumped in the usual manner. Or, if any particular well shows a high temperature in relation to the others, then this well is not pumped out so frequently. A varying head can be maintained on each well to equalize the flow from the input well to the various wells. One set-up for the operation will usually take care of production from 16 to 64 acres. After the viscosity of the oil produced from all of the surrounding wells has been considerably lowered or the temperature substantially increased, then the operation can be moved to a new point in the field. Air, either cold or heated, may now be introduced into the input well to displace a large amount of the residual oil of lower viscosity and increase production by the usual compression methods.

The method and apparatus for secondary recovery of oil by a cyclic system in accordance with this invention may be illustrated by refer-

ence to the following description in conjunction with the accompanying drawings, in which

Figure 1 illustrates diagrammatically one form of system and arrangement of apparatus suitable for the practice of the invention;

Figure 2 illustrates a portion of the apparatus suitable for the practice of a modified form of the invention described with reference to Figure 1; and

Figure 3 illustrates one form of arrangement of input wells, primary producing wells and secondary wells which may be employed in the practice of the invention.

Referring to Figure 1, crude oil is pumped from the producing sand 2 by means of a suitable pump generally indicated at 4 and having a pump rod 6 attached to a jack 8 and is lifted through the well 10 into the conduit 12 to a crude oil storage vessel 14. From storage vessel 14 the oil passes through conduit 16 controlled by valve 18 and is pumped by means of pump 20 through a discharge line 22 and a back pressure valve 24 into a heat exchanger 26. A portion of the oil may also be pumped through conduit 28. Valves 30 and 32 are proportioning valves in conduits 34 and 36, respectively, for proportioning the amount of oil either to tank 38 or the heat exchanger coil 40. Conduit 42 connects the heat exchanger coil 40 with a conduit 44 on the other side of the heat exchanger 26. A conduit 46, provided with valve 48, serves to carry oil from the heat exchanger 26 to the tank or flash drum 38 where it is preferably introduced by means of a spray 50. The oil passing through conduit 44 enters a furnace or pipe heater 52, sometimes referred to as a pipe still, wherein it is heated in coils 54 and then passed through a conduit 56 provided with a valve 58 to the flash tank 38. The level of liquid 60 in tank 38 is controlled in any suitable manner by means of a level control 62 and dump valve 64, and residual oil is removed through conduit 66, heat exchanger coil 68 and conduit 70, controlled by valve 72, to a storage tank 74.

The hot distillate from tank 38 may be recycled in part through line 39, the proportion thereof being controlled by valves 37 and 41.

A line or conduit 76 is provided which connects either to condenser 78 through valve 80 or to well line 82 through valve 84. A receiver tank 86 is provided for the condenser 78 and a conduit 88, having a valve 90, is connected to receiver tank 86 through a pump 92. The conduit 88 also connects to conduit 82 whereby liquid from the receiver tank 86 may be pumped into conduit 82. Conduit 82, which may be referred to as the input conduit, is preferably provided with a pump 94 and leads to the input well 96, which in turn leads to the adjacent oil formation 98 into which the oil vapors are introduced, and auxiliary conduit 100, provided with valve 102, leads to a source of hot, compressed gases which may be employed in accordance with a modified form of the practice of the invention as hereinafter described.

In a typical operation, the oil is picked up from tank 14 by means of line 16 through the valve 18 and the pump 20 and is carried against a pressure of 400 to 1000 pounds. It is discharged through the heat exchanger 68 to pre-heat it by means of the residue from the flash drum or flash tank 38 which is automatically discharged at a certain level through line 66. This preheated oil is then passed through line 44 into the furnace 52, or it may be by-passed

at line 46, preferably into spray 50 to increase the amount of residue from the flash drum or to reduce the amount of vapors passing over through the line 76, or alternately the cool oil from the pump 20 may be passed through a cooling coil 40 to condense back some of the vapors from the flash drum 38, or if the oil is reasonably free from water it may be injected cold into the flash drum 38 through the spray 50.

These various operations may be carried on simultaneously to obtain exactly the right results. The main purpose is to control the amount of overhead distillate going through line 76 so that the residue in reservoir 74 will have the the right characteristics. The amount of residue delivered to tank 74 will vary from 50% to 85%, the latter being suitable, for example, for thin fuel oil and the former being suitable, for example, for asphaltic stock, particularly for roofing purposes. Intermediate stocks may be either fuel oil or lubricating stocks.

The oil is carried through the furnace coil 54 so that it reaches a temperature at the outlet of the furnace of 800° F. This is incipient cracking and will ordinarily produce about 5% to 10% of naphtha or gasoline without producing enough coke in the coil 54 to interfere with operations. The pressure carried in coil 54 is ordinarily about 500 pounds per square inch, this being liquid pressure unless considerable cracking has been effected. Valve 58 may be used to control pressure. With the use of valve 58 the pressure may be carried as high as 1000 pounds per square inch and cracking may be carried on automatically to produce from the generated vapors a pressure in flash tank 38 of, for example, 400 pounds per square inch. The delivery of oil vapors from the flash drum 38 through the lines 76 and 82 is controlled by the valve 84 which may be automatically relieved at the desired pressure, for example, 400 pounds per square inch.

The pressure introduced into the well formation 98 may be maintained either by a hydrostatic head in the well or by a closed casing head 45 in which gases collect to form not only the necessary pressure but also to utilize the input pressure.

The relative amounts of distillate and residue are governed by the temperature in the line 76 50 which will ordinarily be within the range of 400° F. to 750° F. and this may be adjusted to any degree necessary by the use of the coil 40 and spray 50.

If for any reason it is desired to suddenly discontinue injection into the input well, then the vapors may be diverted to the condenser coil 78 and the naphthas collected in receiver tank 86.

This operation goes on preferably 24 hours per day and after the producing wells in the diagram (see Figure 3) have responded as indicated by a rise of temperature, for example, of 20° or more in the formation, then the introduction of hot oil vapors may cease and instead there may be introduced compressed air or gas, either hot or cold.

If it is desired to introduce the gases hot, then an arrangement such as set out in Figure 2 may be used. This consists essentially of a large drum 104 lined with fire brick generally indicated at 106 in which a fuel is burned to produce hot gases of combustion at a temperature of 400° F. to 1000° F. This combustion is carried on at a pressure ordinarily in excess of 400 pounds, or sufficient to allow rapid introduction of these

gases of combustion into the formation of the input well. Compressed air is introduced into the chamber 108 through a conduit 110 and valve 112. Fuel is introduced into chamber 108 through a conduit 114 and back pressure valve 116 and is ignited by a suitable ignition means 118, so that it burns in a refractory tile chamber 120. The conduit 100 connects from the chamber 108 through back pressure valve 102 to the input well of Figure 1. An excess of air is preferably used in this combustion chamber of at least 1000%. In general, the operation involves the introduction of compressed air through the line 110 to maintain the pressure of the air in the combustion chamber, the introduction of gas or oil through line 114 against the pressure in the combustion chamber, the continuous ignition of the fuel by means of a spark or other ignition means 118 and the continuous removal of the gases to the input well controlled by the automatic valve 102 which releases pressure above the desired or necessary amount. A manhole 122 is provided for inspection, cleaning, and the like.

The following illustrates the operation of the invention in one field (Allen County, Kansas):

	A	B	C	D
Gravity, A. P. I. .... degrees	19.2	22.3	28.0	21.8
Gasoline and naphtha content per cent.	0	7.5	32.0	7.5
Burning oil. .... do.	0	10.0	10.0	10.0
Fuel oil residue. .... do.	100	82.5	51.5	82.5
Viscosity. .... ° F.	112			44
Cold test. .... ° F.		0		-20
B. S. .... per cent.	1			0

"A" is the natural crude as it comes from the ground at a depth of 875 feet.

"B" is "A" which has been brought to incipient cracking at 800° F. and is then flashed into a still to remove 17.5% of gasoline and distillate. This amount of cracking is insufficient to form any appreciable amount of carbon so that it could be directly introduced into a well advantageously without clogging the pores in the sand. At the same time it not only heats and fluxes the oil in the formation but reduces the viscosity by solvent action also. Its viscosity is well below the viscosity of the crude. However, the best effect is attained by the introduction of the hot overhead vapors which when condensed have a viscosity of 30 and have a perfect solvent action on the crude. The 82.5% residue has a viscosity practically the same as original crude (104) and cold test of 5° F.

"C" is a typical "synthetic crude" oil made from "A" and contains an amount of carbon which eventually occludes the input well but is very effective in increasing production.

"D" is the crude oil after the 17.5% taken out of "B" is mixed with 82.5% of the natural crude in the ground. The viscosity is much less than one half and the cold test is 20° lower than the crude and the blend is perfectly uniform. This illustrates the change of character of the crude in the ground after injection of vapors.

This process results in the thinning of the natural crude oil in situ, thereby increasing its production and, secondly, the dehydration of the crude oil for a high grade marketable fuel oil with an improvement in all operations and products. The results are obtained in a closed cyclic system and the raw materials whereby the improved

results are produced are derived from the crude oil itself. Thus, the invention is especially applicable to wells which have ceased to flow or from which the oil can be extracted only with difficulty. In practicing the invention it is essential that the pressure in the cyclic system be greater than the pressure in the formation and the latter may vary within relatively wide limits, say 100 pounds per square inch to 1000 pounds per square inch, depending upon the particular formation. The pressure in the cyclic system may be derived either by virtue of the temperature of the recycled materials, which will usually be within the range of 650° F. to 1000° F. in conduit 56, or by virtue of additional pressure supplied through suitable pumping means. The temperature of the overhead distillate (kerosene, gasoline and gas oil) passing through line 16 will ordinarily be at least 400° F. and the temperature of hot gases introduced through conduit 100 will ordinarily vary within the range of 400° F. to 1000° F.

While the illustration given above applies to the use of oil from the least from which secondary recovery of oil is being taken, in many cases it is advantageous to bring in oil from sources outside the lease. These problems are largely economic in character. Where oil such as cheap gas oil may be had more cheaply than crude oil then such outside sources are desirable. As previously indicated, the crude distillate may contain kerosene, gasoline and gas oil. When the lighter distillates are used then it is not necessary to have as substantial equipment as in those cases where the oil to be injected into the formation is to be subjected to cracking. Cracking equipment is mechanically more substantial and is very much more expensive than mere heating equipment so that cheap low viscosity oils of any character may often be used economically without cracking. The introduction of the heated oil will ordinarily be continuous and more or less simultaneous with the withdrawal of crude from any adjacent point. This, however, is not necessarily the case. The treating oil may be intermittently introduced and the crude intermittently withdrawn even from the same well often with very satisfactory results. The treatment opens up the sand and cleans it off as well, reducing the viscosity and increasing the area into which oil may flow from surrounding formations.

Having thus described the invention, what I claim as new and desire to secure by Letters Patent of the United States is:

That improvement in methods of increasing the recovery of heavy, viscous crude petroleum from subterranean deposits thereof, which includes the following steps: (1) extracting petroleum from the subterranean deposit (2) heating at least a portion of the extracted petroleum to a temperature of 650° F. or above in order to obtain a lighter fraction therefrom (3) thereafter introducing into the deposit at least a part of the lighter fraction thus obtained and (4) causing said fraction to penetrate to a considerable distance within the deposit in order to decrease the viscosity of the residual heavy petroleum within the deposit and to facilitate the further recovery of such petroleum therefrom.
